UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

UPPER-FORMING MACHINE.

1,119,039.

Specification of Letters Patent.

Patented Dec. 1, 1914.

Application filed January 3, 1913. Serial No. 739,977.

To all whom it may concern:

Be it known that I, ADAM H. PRENZEL, a citizen of the United States, residing at Halifax, in the county of Dauphin and State 5 of Pennsylvania, have invented certain Improvements in Upper-Forming Machines, of which the following description, in connection with the accompanying drawings, is a specification, like reference characters on 10 the drawings indicating like parts in the several figures.

This invention relates to machines for preparing uppers of stitch-down shoes for the attachment of the sole and particularly 15 to machines for preparing the heel end of a stitch down upper to receive the sole.

In forming an outturned flange upon the lower edge of the heel end of a shoe upper by turning out a marginal portion of the 20 upper of a width sufficient to form a flange of the desired width, it will be obvious that the edge of this flange, if it is simply turned out into a position at substantially right angles to its position before the turning operation, will have a peripheral measurement greater than its original peripheral measurement and that this increase in the peripheral measurement will be greater for a wide 25 flange than for a narrow flange. If it is attempted, therefore, to form the flange by simply turning the upper out, without any 30 preliminary shaping operation, the upper must either be stretched considerably to provide for the increased peripheral measurement of its edge or it must be provided with cuts or notches to permit the flanging operation. Otherwise there will be liability 35 of tearing the upper in such a way as to spoil its appearance in the finished shoe. Moreover, a flange formed in the manner 40 just described presents an unsightly appearance at the heel end of the shoe upper since the flange projects too far beyond the contour of the heel to permit the formation of 45 a heel having a neat appearance.

To avoid either injuring the upper in the flanging operation or forming a flange which projects too far beyond the side of the heel it has been proposed to gather in the 50 upper along the flange turning line preparatory to the flanging operation, whereby a fullness is provided which permits the formation of a flange having only a slightly increased peripheral measurement and projecting only slightly beyond the side of the

heel. This mode of flanging the heel end of a stitch-down shoe upper has been successfully practised and an object of the invention is to provide simple and efficient means for flanging the heel end of a shoe upper 60 which will utilize the important principles of operation above set forth.

To this end the invention contemplates the provision of means for first forming a crease in the heel end of the shoe upper along 65 the line about which it is desired to turn the flange, whereby the upper will be gathered in along the flange turning line, and then to hold the upper in the creasing means while the projecting portion of the upper 70 from which the flange is to be formed is turned out upon said creasing means.

An important feature of the invention is the provision of simple, efficient and easily 75 interchangeable means for shaping the heel end of the upper and maintaining the shape of this part of the upper during the flanging operation.

Another important feature of the invention is the provision of novel means coöperating with the creasing means for effecting 80 the turning out and the pressing out of the outturned flange.

Other important features of the invention are means for presenting the work, together 85 with novel means for locating the work in the machine; novel means for holding the work in proper position as it is presented to the different mechanisms which are to operate in succession, and a novel arrangement 90 of the creasing elements whereby the creasing operation may be performed effectively at the forward end of the heel portion of the upper, in the region of the shank.

Still other important features and objects 95 of the invention will be apparent when the following description and claims are considered in connection with the accompanying drawings, in which—

Figure 1 is a side elevation of the machine 100 embodying the invention; Fig. 2 is a front elevation; Fig. 3 is a longitudinal section through the machine, showing the parts in operative relation to each other; Fig. 4 is a perspective detail illustrating the mode of 105 operation of the gage for determining the width of the flange; Fig. 5 is a plan view of the machine; and Fig. 6 is a section illustrating the creasing operation.

The illustrated machine is adapted to be 110

mounted upon a bench and all of the elements of the machine are manually controlled. It will be understood, however, that these parts may be so connected as to operate automatically in proper succession, whereby the machine could be driven by power.

One of the principal elements of the machine is the support 2 for the shoe upper to be operated upon, which is of such a form that it acts to shape the heel end of the upper. This shaping and supporting means is provided with a crease receiving groove 4 which may be formed in a plate 6 attached to the upper face of said support and is carried upon a slide 8 arranged to slide back and forth in guides 10 in the base 12 of the machine into and out of inoperative position. The creasing means comprises side engaging plates 14 and 16 and an end engaging plate 18 which are adapted to engage the outer face of the upper and force a portion thereof into the crease receiving groove 4 to form a crease in said upper.

Means is provided for moving the slide 8 into and out of operative relation to the creasing means and the illustrated means comprises a lever 20 provided at one end with a handle 22 and connected at its other end by means of a link 24 with the slide 8, the lever 20 being fulcrumed at 26 on a vertical post or stud on the base 12.

The side plates 14 and 16 of the creasing means are fastened to the upper faces of levers 28 and 30 respectively which are pivoted at 32 and 34 upon a table 36 raised above the base 12 by supports 28. The central portion of the table 36 is cut away and the end of the table toward the upper support 2 is open so that said upper support may be moved into said central opening in said table. The side plate supporting levers 28 and 30 are movable about vertical axes to bring the plates into engagement with the sides of the upper and force the upper into the crease receiving groove 4. These plates are normally maintained in their position of greatest separation by a spring 40 connected at its ends to studs upon the ends of the levers 28 and 30 remote from the plates 14 and 16. Plates 14 and 16 are each slightly curved at their rear ends so that they tend to engage the upper also at the rear end of the heel and the space between the upper engaging portions of these plates at their rear ends is filled out by the end engaging plate 18 which is carried upon a stud 42 formed upon the table 36 and of such height that it brings the plate 18 into the plane of the plates 14 and 16. The plates 14 and 16 can be moved positively into crease forming relation to the upper by means comprising a rotary eccentric member 44 located between the rearward extensions of the levers 28 and 30 and carried

upon a short vertical rock shaft 46 extending through the table 36, the lower end of this rock shaft having rigidly attached thereto an arm 48 connected by a link 50 to a lever fulcrumed upon the base 12 and provided with a handle 56 by which it may be operated.

The rotary member 44 may be turned by its connection to the lever 52 into such position that its greatest diameter comes between the extended ends of the levers 28 and 30 and turns said levers about their pivots 32 and 34 to force the crease forming plates 14 and 16 into engagement with the sides of the upper to be operated upon. The amount of opening movement of said plates 14 and 16 may be limited by a stop 58 comprising a set screw threaded through a laterally extending support 60 attached to the table 36 and provided with a set nut 62, this stop being arranged to engage and limit the movement of the arm 48 in a direction to permit the spring 40 to draw the rear arms of the levers 28 and 30 toward each other.

In operation the shoe supporting and shaping means 2 is carried forward with the slide 8 into such position that the shoe upper may conveniently be placed upon said means. If it is desired to gage the width of the flange to be formed more accurately than can be done by the eye of the operator, while the shoe upper support 2 is in its forward position out of operative relation with the creasing means gaging means may be brought into operative relation to said support, whereby the amount of projection of the upper above the crease receiving groove 4 may be determined. The illustrated gaging means comprises a member 64 of substantially the same contour as the plate 6 in which the crease receiving groove is formed, whereby it may enter and substantially fill the space within the projecting margin of the shoe upper, this member being carried upon an arm 66 arranged to turn upon the vertical post 68 and supported upon a collar 70 rigidly attached to said post, the arm being so proportioned that as it swings about the post 68 it will bring the member 64 into the space within the projecting margin of the shoe upper.

The member 64 is provided with a gage plate 72 which projects over the sides of the upper and determines the amount of projection of the upper above the plate 6 and with another gage plate 74 which projects over the rear end of the upper and determines the amount of projection of the upper at this end above the plate 6. While the upper is thus located by the gaging means the operator moves the upper support 2 toward its operative position within the creasing means and as the support moves rearwardly the rear end of the upper is engaged by a retaining member 76, by which

the upper is pressed against the support 2 and maintained in the relation to said support which has been determined for it by the gaging means. The gaging means can now 5 be moved out of operative relation to the upper to facilitate the further movement of the support 2 and the upper into the creasing means. The upper retaining device 76 is carried upon the forward end of a rod 78 10 sliding in the vertical stud 42 and in a second vertical stud 80, a longitudinal groove being provided in the upper face of said rod into which projects a screw 82 to prevent the rod from turning about its longitudinal 15 axis.

The retaining member 76 is kept in engagement with the shoe as the support 2 is moved into operative relation to the creasing means by a spring 84 confined between 20 a collar 86, pivoted upon the rod 78 and the stud 80, the spring being compressed as the rod 78 slides toward the studs 42 and 80.

The upper having been brought into operative relation to the creasing means and 25 the creasing means having been operated through the lever 52 to force the upper into the crease receiving groove 4, it will be apparent that the margin of the upper projecting beyond the creasing plates 14, 16 30 and 18 will be given a tendency to turn out by reason of the fullness along the flange line and by reason of the further fact that the upper side of the crease receiving groove 4 overhangs considerably the lower side.

35 In order to complete the turning process and also to press and smooth the flange out, means has been provided which may be brought into engagement with the flange and which can be operated to progressively turn 40 out and smooth out this flange. The illustrated means comprises a roller 88 mounted to turn about a short shaft supported by hangers 90 depending from a slide 92 arranged to slide in guides 94 in the cross-head 96. The cross-head 96 has vertical cuplike bearings which receive and are guided upon vertical posts 68, 98, 100 and 102, each of these posts being provided with a collar rigidly confined thereon and a spring between the cross-head bearing and said collar by which the cross-head is maintained normally in its highest position. The cross-head may be depressed to bring the roller into operative relation to the upper 45 confined between the work support 2 and the creasing means, by connections with a treadle 103 comprising a link 104 pivotally connected at one end to the cross-head and connected at the other end to an arm 106 50 upon a rock shaft 108 having a second arm 110 rigidly confined thereon, the arm 110 being connected to said treadle.

The flange turning and pressing out operation is preferably performed by moving 55 the roller from the shank toward the rear

end of the upper and in order to effect this movement of the roller means has been provided for moving the slide 92 forward and backward upon the cross-head 96. The illustrated means comprises a lever 112 fulcrumed at 114 between ears upon an inclined support 116 upon the cross-head, this lever being connected by a link 118 to the rear end of the slide 92. At its front end is a handle 120 arranged in a convenient position to be grasped by the operator.

Having thus described my invention what I claim as new and desire to secure by Letters Patent of the United States is:—

1. In a machine for flanging shoe uppers, 86 means for supporting the upper above and below a crease line for a creasing operation, said means being constructed to provide a space therebetween into which the upper may be forced, means for forcing the upper 85 between said supporting means to form a crease in said upper and means for turning the upper out upon said creasing means.

2. In a machine of the class described, the combination with creasing means, of means 90 shaped to enter and to shape the heel end of a shoe upper and having about its periphery a crease receiving groove, said means being arranged to present said upper in such operative relation to said creasing means that 95 said creasing means will force the upper into said crease receiving groove.

3. In a machine for flanging shoe uppers, 100 means for entering and shaping the inside of the heel end of the shoe upper provided with a crease receiving groove, so located as to determine a flange line, means for creasing the upper along the flange line arranged to force the upper into said groove, and means for turning the upper out about the 105 flange line thus determined.

4. In a machine of the class described the combination with means shaped to receive the end of a shoe upper, having formed therein a crease receiving groove so located 110 as to determine a flange line for a sole attaching flange, means arranged to engage the upper at the sides and at the end of the heel portion thereof and to force the upper into said groove to form a flange crease 115 therein, and means movable from the shank portion of the shoe toward the heel portion thereof for turning out a flange upon said crease forming means.

5. In a machine of the class described, 120 means for shaping the heel end of a shoe upper, means for gathering in and creasing the upper along a flange line constructed to impart to the flange portion of the upper a tendency to turn out and means for completing the turning out of the flange about 125 said flange line comprising a roller arranged to roll the upper out.

6. In a machine of the class described, the combination with creasing means and means 130

for shaping the heel end of a shoe upper, said means being relatively movable into operative relation to each other after the shoe has been presented to said shaping means, and means normally out of operative relation to said shaping means adapted to engage the upper during the relative movement of said shaping means and said creasing means to hold the upper upon said shaping means as it is presented to said creasing means.

7. In a machine of the class described, a member provided with a crease receiving groove, said member being adapted to enter and support the heel end of a shoe upper for the creasing operation, means adapted to force the upper into said crease receiving groove to form a crease in said upper, said member and said means being normally separated whereby said upper may easily be presented to said member for the creasing operation, and means for retaining the upper upon said member during the relative movement of said member and said crease forming means into operative relation.

25 8. In a machine for flanging shoe uppers, means for forming a crease in the upper along the flange line, said means being provided with a crease receiving groove having an overhanging lip upon the flange-engaging side of said means.

30 9. In a machine for flanging shoe uppers, means for forming a crease in the upper along the flange line comprising a member having a crease receiving groove, said member being formed with an overhanging lip upon the flange-engaging side of said groove.

35 10. In a machine for flanging shoe uppers, means for creasing the upper along the flange line, and means for turning out the projecting margin of the upper after the creasing operation.

40 11. In a machine for flanging shoe uppers, means for creasing the upper along the flange line to form a flange, and means for

pressing the flange out upon said creasing means after the creasing operation.

45 12. In a machine for flanging shoe uppers, means for gathering in and creasing the upper along the flange turning line to form a flange, and means for turning out the flange comprising a roller arranged to roll the upper out upon said gathering-in means.

50 13. In a machine for flanging shoe uppers, means for gathering in the upper along the flange turning line, and means for turning out the upper upon said gathering-in means comprising a roller supported normally above said means, out of operative relation thereto, and arranged to be depressed into 60 operative relation to said means.

55 14. In a machine for flanging shoe uppers, upper creasing means comprising a member adapted to operate upon the inside of the shoe and having a crease receiving groove, 65 and a stationary member outside said shoe against which the upper is adapted to be forced by said inside member, said outside member being shaped to enter said groove to effect a creasing of the upper.

60 15. In a machine for flanging shoe uppers, upper creasing means comprising a member adapted to operate upon the inside of the shoe and having a crease receiving groove, and coöoperating members upon the outside 75 of said shoe comprising a member adapted to engage the shoe at its heel end, and pivoted side engaging members movable toward each other to complete the creasing operation after the upper has been forced into 80 said crease receiving groove by said end engaging member.

In testimony whereof I have signed my name to this specification in the presence of two subscribing witnesses.
